UNITED STATES PATENT OFFICE

2,539,858

DRIVE MECHANISM

Elmer B. Offutt, Kansas City, Mo., assignor to
 The Indiana Steel Products Company, Chicago,
 Ill., a corporation of Indiana

Application May 12, 1947, Serial No. 747,556

3 Claims. (Cl. 242—55)

1

My invention relates to a drive mechanism for imparting a controllable velocity to a medium.

It is an object of my invention to provide an improved drive mechanism for a belt-like medium, such as paper tape, wherein the tendency of the medium to slip relative to the drive mechanism is minimized.

A further object of my invention is to provide an improved drive mechanism capable of imparting a controllable linear velocity to a belt-like medium such as paper tape, and which has features of construction, combination and arrangement, whereby the natural operation of the mechanism maintains the drive in good operating condition.

Further, it is an object of my invention to provide an improved drive system for imparting linear velocity to a belt-like medium such as paper tape which is particularly adapted for use in connection with magnetic recording and reproducing equipment.

Yet another object of my invention is to provide an improved drive member for imparting controlled velocities to a medium such as paper or the like.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings.

On the drawings:

Figure 1 is a somewhat diagrammatic top view of a magnetic recording and reproducing mechanism incorporating the features of my invention.

Figure 2 is a somewhat diagrammatic view of the mechanism of Figure 1 as seen with the top removed.

Figure 3 is a side view of the apparatus of Figures 1 and 2 but with the medium removed, and

Figure 4 is a cross section view through the drive member of Figure 1.

As shown on the drawings:

In Figure 1, 10 and 12 are supporting devices for the lengthy medium 14, in the particular structure shown, 10 and 12 are spools and medium 14 is a paper tape such as manila rope stock treated for use in a magnetic recorder. This treatment may, for example, comprise a coating of magnetic particles obtained by passing the paper through a vinyl acetate-acetone solution

2

containing suspended magnetic particles. In passing between spools 10 and 12, medium 14 passes over drive capstan 16 and recording and reproducing head 18. Head 18 is electrically connected to unit 20 which is a magnetic recorder and reproducer. Recorder and reproducer 20 is arranged so that in the recording operation time variations in the intensity of a signal, such as speech or music, are converted into corresponding time variations in the magnetic field about head 18. Thus, as the medium 14 is passed under head 18 at controlled linear velocity, the degree of magnetization thereof along its length is altered in accordance with the time variations in the signal applied to recorder 20, thereby imparting to medium 14 longitudinal variations in magnetization in accordance with the impressed signal. In the reproducing operation, magnetic recorder and reproducer 20 is connected so that the induced voltages in head 18 associated with time variations in the magnetic field caused by the variations in magnetization of medium 14 as it passes thereover are converted into corresponding signal variations, such as, for example, the intensity of a sound wave, thereby reproducing the signal corresponding to the magnetization of medium 14.

It is the purpose of motor 22, Figures 2 and 3, to rotate capstan 16 so as to impart linear velocity to medium 14. Flywheel 24 maintains substantially constant the rotational velocity of capstan 16 despite random variations in the torques applied to the shaft of motor 22, thereby causing the peripheral velocity of capstan 16 to be maintained substantially constant. In addition to driving capstan 16, motor 22 is connected by pulley 26 to tend to drive spools 10 and 12 in respective opposite directions so as to tend to cause medium 14 to wind on both spools acting in opposition to each other. This tendency is imparted to spool 10 by belt 28 which rides on pulley 26 and pulley 30. A controllable tension is placed on belt 28 by idler pulley 32, the magnitude of this tension being determined by the position of mounting plate 34 about axis 36. Spool 12 tends to be driven in the windup direction by means of belt 38 which rides on pulley 40.

The diameters of pulleys 26, 30 and 40 are so proportioned relative to the diameter of capstan 16 that medium 14 tends to wind upon spool 12 at a rate greater than it tends to pass across capstan 16. As a consequence, medium 14 is maintained taut between capstan 16 and spool 12.

It is the function of pinch wheel 42 to urge medium 14 against capstan 16 so as to achieve

pressure therebetween and a good frictional engagement. As will be evident from Figure 2, this wheel is mounted upon spindle 44 which is supported by plate 34 so that as plate 34 is twisted in the clockwise direction relative to axis 36, the frictional engagement between medium 14 and capstan 16 is increased. From Figure 2 it will further be evident that clockwise rotation of plate 34 about axis 36 swings idler pulley 32 in a disengaging direction so as to cause pulley 28 to assume a loose condition. The position of plate 34 about axis 36 is determined by operating handle 46 which projects above the unit as shown in Figures 1 and 3.

When operating handle 46 is in the "forward" position shown in the solid lines of Figure 1, the belt 28 is in a relatively loose condition and slips over pulleys 26 and 30 with relative ease. Furthermore, the pressure exerted between pinch wheel 42 and capstan 16 is relatively great and causes good frictional engagement between medium 14 and the surface of capstan 16; thus imparting linear velocity to medium 14 of value corresponding to the angular velocity of capstan 16. Thus, the action of capstan 16 overcomes the action of belt 28 and medium 14 is withdrawn from spool 10 at a controllable linear velocity determined by the angular velocity of capstan 16. Simultaneously, medium 14 is wound upon spool 12 by reason of the action of belt 38. Since belt 38 tends to drive spool 12 at an angular velocity exceeding that corresponding to the linear velocity imparted by capstan 16 to medium 14, belt 38 slips and medium 14 is held taut between capstan 16 and spool 12.

When operating handle 46 is rotated in the counterclockwise direction to the position shown in the dashed lines of Figure 1, pinch pulley 42 is swung to a disengaging position relative to capstan 16 as shown by the dashed lines of Figure 1. In this condition, wheel 42 does not press medium 14 against capstan 16 but instead permits that pressure to assume the relatively small value associated with the torque of belts 28 and 38, tending to rotate spools 10 and 12. Simultaneously, wheel 32 swings against belt 28 in direction to increase the tension thereof, thereby increasing the frictional engagement between that belt and pulleys 26 and 30. In this condition, the torque exerted on spool 10 as a consequence of pulley 30 is sufficiently great to overcome the reduced winding forces associated with rotation of capstan 16 and the tendency of belt 38 to rotate spool 12 in the direction to wind medium 14 thereon. Medium 14 is accordingly transferred from spool 12 to spool 10 at linear velocity corresponding to the angular velocity of spool 10 and the body of the medium 14 contained on that spool.

From the above description of operation, it will be evident that operation of the mechanism of Figures 1, 2 and 3 depends entirely on the frictional engagement between medium 14 and capstan 16 to impart uniform linear velocity to medium 14 as it passes from spool 10 to spool 12. If this frictional engagement is inadequate, medium 14 will slip relative to capstan 16 and variations in the linear velocity of medium 14 will result. The consequent time variations in the induced voltage in head 18 will cause unsatisfactory reproduction of the signal and hence render recording and reproduction unsatisfactory. I have discovered that particularly good frictional engagement can be achieved between medium 14 and capstan 16 if the surface of the

latter is made of a lead alloy, such as a lead-tin alloy. A construction of wheel 16 in accordance with this aspect of my invention is shown in Figure 4 which is a cross section view through the axis IV-IV, Figure 1, and which shows a capstan having an inner supporting portion 48 having a lead alloy covering 50. I have found that a particularly suitable material for the outer sheath of capstan 16 is a lead-tin alloy comprising 65% lead and 35% tin. Other materials containing lead give satisfactory performance, however.

A further feature of my invention resides in the use of pressure pad 52, Figure 1, which is yieldably supported by cantilever spring 54 from mounting plate 34 as will be evident from examination of Figure 2. Pressure pad 52 is of felt or similar material capable of exerting uniform pressure against capstan 16. When mounting plate 34 is rotated in the counterclockwise direction, spring 54 is accordingly rotated in a direction causing pressure pad 52 to press against the surface of capstan 16. Thus, the pressure exerted by pressure pad 52 against capstan 16 is determined by the position of switch 46 and hence by the direction of travel of medium 14.

It will be observed that when the unit is operating in the reverse direction with medium 14 being rewound on spool 10 from spool 12, capstan 16 nevertheless rotates in the clockwise direction against the motion of the medium 14. In addition, as pressure pad 52 bears against medium 14 and presses this medium against capstan 16, a restraining force is imparted to medium 14 which causes the medium 14 to be under essentially uniform and constant tension depending upon the pressure exerted by pressure pad 52, thereby insuring that said medium will be rewound smoothly and firmly onto spool 10. As pressure pad 52 bears against medium 14 in this condition, medium 14 tends to clean capstan 16, thereby rendering the surface of sheath 50 smooth and symmetrical. This maintains the capstan 16 in good operating condition so that when it is operated in the forward position the linear velocity imparted to medium 14 is constant.

In the case of a magnetic recorder and reproducer it is particularly important that the capstan 16 be of uniform radius and have no flat or rough spots. Otherwise periodic variations in linear velocity are imparted to medium 14 and "wow" results. It will be observed that with the system described herein, the capstan 16 is polished in direct proportion to the amount of use of the unit so that the polishing action corresponds to the natural effect tending to cause capstan 16 to deviate from a perfectly symmetrical condition.

Mechanisms having features in common with the present invention are disclosed and claimed in my copending application (Case 46,592) and the copending application of myself and Hugh A. Howell (Case 46,941).

While I have shown a particular embodiment of my invention, it will, of course, be understood that I do not wish to be limited thereto since many modifications in the elements employed and the structure disclosed may be made without departing from the spirit and scope thereof. I, of course, contemplate by the appended claims to cover any such modifications as fall within the true spirit and scope of my invention.

I claim as my invention:

1. A drive mechanism for imparting velocity to a medium including a capstan to engage said

medium, mechanism to rotate said capstan so as normally to impart velocity to said medium, a drive selectively operable to move said medium in opposition to the rotation of said capstan, and a pressure pad to press said medium against said capstan when said medium moves in opposition to the rotation thereof so as to cause said medium to polish said capstan to a uniform radius.

2. A drive mechanism for imparting velocity to a medium including a capstan to engage said medium, mechanism to rotate said capstan so as normally to impart velocity to said medium, a drive selectively operable to move said medium in opposition to the rotation of said capstan, a wheel and a pressure pad alternately engageable to urge said medium against said capstan, and elements connecting said wheel and said pressure pad to said drive so that said wheel engages when said medium moves with said capstan and said pressure pad engages when said medium moves in opposition thereto.

3. In combination a pair of medium supporting devices, a longitudinal flexible medium wound about said devices to be transferred therebetween, a capstan to engage said medium to tend to transfer said medium from one of said devices to the other, a unidirectional drive for said capstan, mechanism to urge said medium against said capstan including a pinch wheel and a pressure

pad alternately engageable with said medium, a drive to tend to rotate said devices in opposed directions to tend to wind said medium thereon, said drive being adjustable to wind said medium in opposition to the rotation of said capstan, said drive and said mechanism being interconnected so that said pressure pad engages said medium when said medium travels in opposition to the rotation of said capstan.
